UNITED STATES PATENT OFFICE.

EDWIN CALDWELL, OF NEW YORK, N. Y.

PIPE HOLDER.

Application filed October 30, 1924. Serial No. 746,777.

This invention relates to pipe supports and particularly to pipe supports having additional functions, such as the supporting and concealing of a supply of matches and the providing of a striking surface for said matches.

An object of the invention is to provide an improved device for this purpose which will be light, simple and inexpensive in construction; which will effectively support any style of pipe with the bowl upright and with the mouth end of the stem out of contact with all surfaces; which may be formed largely or entirely of bent wire and stamped or bent sheet metal; with which the assembly operations are reduced to a minimum; and which is susceptible of embodiment into various pleasant, attractive and artistic designs.

A further object is to provide an improved device which will support safety match boxes in such a manner that the matches will be conveniently accessible; with which the striking surface of the boxes will be conveniently accessible; and which will present an attractive appearance.

Various other objects and advantages will be apparent from the following description of an embodiment of the invention and the novel features will be particularly pointed out in the accompanying claims.

In the accompanying drawing:—

Fig. 1 is a side elevation of a combined match receptacle and pipe support;

Fig. 2 is a plan of the same;

Fig. 3 is an end view of the match receptacle, the pipe holder being omitted;

Fig. 4 is a plan of a different form of pipe support constructed in accordance with the invention;

Fig. 5 is an end elevation of the same; and

Fig. 6 is a perspective of a further and modified embodiment of the pipe support.

Referring particularly to Figs. 1, 2 and 3, the base member 1 comprises an open ended parallelopiped, which is preferably formed by binding a strip of stamped sheet metal transversely at spaced points, the two abutting edges completing the same being unconnected for a purpose which will hereinafter appear.

Integral tongues 2 are provided upon opposite edges at points corresponding to one of the walls of the parallelopiped and these tongues are bent downwardly in a direction away from one another as shown in

Figs. 1 and 2 to form supporting feet for the parallelopiped. The parallelopiped is of such internal proportions that it will snugly receive the outer shell 3 of the ordinary safety match box and frictionally hold the same therein. The shell is inserted therein by sliding it through one of the open ends of the parallelopiped. The two abutting edges of the strip, which completes the parallelopiped, are unconnected so that when the shell is inserted, one of the walls, adjoining the abutting edges, must be sprung outwardly slightly in order to allow the outer shell of the match box to enter so that the frictional grip upon the shell will be increased without offering too great a resistance or hindrance to the insertion of the outer shell. Either one or both side walls of the parallelopiped will be provided with apertures or open windows 4 through which the striking surface 5 of the match box shell will be exposed to permit the striking of matches upon such striking surface. Since a striking surface always forms part of a new box of matches, the insertion of a new shell will provide a new striking surface. The inner or container part 6 of the match box may be shifted endwise in either direction to permit of the removal of the matches as desired.

The upper horizontal wall of the parallelopiped is drawn upwardly in a transverse direction for a portion of the width of the top and the ends of the drawn portion cut so as to provide a raised eyelet 7, the ends of which constitute two aligned spaced sockets for a purpose which will hereinafter appear.

The support for the pipe is formed from a stretch of wire 8 which is bent intermediate of its ends into a somewhat U-shape as at 9, the cross arm of the U portion being approximately semi-circular and of a diameter slightly greater than the usual diameter of the bowl of a pipe so that the bowl of the pipe may be inserted into the U-shaped portion as indicated in dash lines in Fig. 1. The portions of the wire at the ends of the U portion are bent downwardly as at 10 (see Fig. 1) until they strike the upper surface of the parallelopiped at one end thereof, the sections 10 being curved toward one another until they reach the upper surface of the parallelopiped. The sections 10 do not entirely meet one another but are turned in a direction away from the U-shaped por-

tion as at 11 and extend in nearly parallel stretches 12 toward the opposite end of the parallelopiped but rising from the surface thereof in an inclined direction. When the stretches 12 are approximately over such opposite end of the parallelopiped or match enclosure, they curve downwardly and obliquely away from one another as at 13 until they approximately reach the plane of the upper surface of the match enclosure and then extend along and in contact with the upper surface of the parallelopiped or match enclosure as at 14. The ends 15 of the wire are then bent toward one another and enter the sockets at the opposite ends of the eyelet 7. When a pipe, shown in dotted lines in Fig. 1, is placed upon the support, the bowl is inserted into the U-shaped portion so as to be supported in an upright position by the section 9 and with the stem of the pipe extending along and supported by the stretches 12. By reason of the inclination of the stretches 12, the mouth piece end of the pipe, regardless of the shape of the stem, will always be supported above and out of contact with any surface upon which the parallelopiped may rest and out of contact with the parallelopiped itself so that if there is any saliva upon the mouth piece, it will not be smeared upon any object and at the same time will not be contaminated. The wire pipe prop will be rigidly attached to the match box enclosing shell in the manner shown, since the stretches 14 will prevent rocking of the wire prop to the left in Fig. 1 and the engagement of the sections 11 with the upper surface of the parallelopiped will prevent rocking of the wire pipe prop in the reverse direction. The parallelopiped may be conveniently formed by stamping and bending the same from sheet metal and the wire support may be formed in automatic wire bending machinery so that the cost of manufacturing and assembling is a minimum and a superior product is obtained.

In Figs. 4 and 5 another embodiment of the invention is illustrated in which the base member 16, forming the support for the wire pipe guard 8^a is a flat stamping of sheet metal, having one end formed with teeth 17 in the edges so that that end may be used as a pipe bowl reamer for removing encrustations from pipe bowls. In this form of the device, the stretches 12^a of the pipe guard are cut off at rather short distances beyond the section 10^a and the severed ends are inserted into sockets 18 which are formed by rolling toward one another tongues on the edge of the base member 16 upon the same face of the base member. The wire pipe prop may be removed readily from the base part by merely withdrawing the section ends 12^a from the sockets 18. In this embodiment of the pipe prop, the parts corresponding to

similar parts in the preceding embodiment are designated by similar characters with the exponent "a". The pipes are supported in this prop in the manner similar to that shown in Fig. 1 except that the pipe stem will extend along the base member 16, but out of contact therewith.

In Fig. 6 I have illustrated in perspective another embodiment of the invention in which the wire pipe prop of the character shown in Figs. 1 and 2 is attached to a different form of base member. The base member 19 is a flat stamping of sheet metal, having at one end a rolled tubular bearing 20 with unrolled ears 21 at both ends of the bearing 20 so that when the ends 15 of the wire prop are inserted into the ends of the bearing 20, the stretches 14 will rest against the ears 21 to an extent sufficient to prevent rotation of the wire prop support in a direction to the left in this figure. The engagement of the prop with the upper face of the base member will prevent rotation in the other direction and, therefore, a comparatively rigid structure is obtained by the mere insertion of the ends of the wire prop into the opposite ends of the bearing 20. A pipe may be supported in this embodiment in the same manner as shown in Fig. 1.

In all of the different embodiments which have been illustrated the pipe will be supported with the bowl upright and out of contact with the surface upon which it is desired to be supported so that the heat of the bowl will not be transmitted to furniture or other objects upon which one desires to support the pipe and with the bowl firmly supported in an upright position, and there will be no danger of ashes falling therefrom and injuring furniture or other objects over which the pipe is supported. Each form of the support is extremely light, simple, practical, convenient and relatively inexpensive.

It will be understood that various changes in the details, which have been herein described and illustrated in order that the nature of the invention may be understood, may be made by those skilled in the art within the principle and scope of the invention as expressed in the appended claims.

I claim:

1. In a pipe support, a base member having sockets, and a wire pipe bowl prop having its ends received in said sockets and intermediate of its ends bent to form a partial enclosure in which a pipe bowl may be supported in an upright position.

2. In a pipe support, a base member having sockets, and a wire strip bent intermediate of its ends to form a U-shaped fence-like enclosure for receiving and propping in an upright position a pipe bowl, the end portions before entering the sockets being bent downwardly from the U-shaped portion and then at an angle to the downward-

ly extending sections and in a direction away from the enclosure section to form a rest for the pipe stem when the pipe bowl is in the enclosure.

5. 3. In a pipe support, a base member having a portion thereof bent to form a clamp, and a wire pipe bowl prop having its ends

clamped by said base member and having its intermediate portion bent to form a partial enclosure in which a pipe bowl may be supported in an upright position.

In witness whereof, I hereunto subscribe my signature.

EDWIN CALDWELL.
